STUD-PLATE UNIT FOR HOSE SUPPORTERS
AND THE LIKEWalter S. Painter, Middlebury, Conn., assignor to
Waterbury Buckle Company, Waterbury, Conn.,
a corporation of Connecticut

Application October 27, 1942, Serial No. 463,467

2 Claims. (Cl. 24—245)

The present invention relates to improvements in fittings for use on hose-supporters and other garment-supporters, and relates more particularly to improvements in stud-plate units for such supporters, i. e., fittings adapted to be suspended from webbing or the like and having a stud-projection for cooperation with a loop for holding hose or other items of personal wear.

One of the objects of the present invention is to provide a superior stud-plate unit which may be produced at a low cost for manufacture and which will effectively serve as a garment-supporting member.

Another object of the present invention is to provide a superior stud-plate unit which may be readily produced from sheet materials such, for instance, as from sheet steel, sheet brass, or sheet synthetic resin.

With the above and other objects in view, as will appear to those skilled in the art from the present disclosure, this invention includes all features in the said disclosure which are novel over the prior art.

In the accompanying drawing, in which certain modes of carrying out the present invention are shown for illustrative purposes:

Fig. 1 is a view in front elevation of the lower portion of a hose-supporter in which is included a stud-plate unit embodying the present invention;

Fig. 2 is a longitudinal sectional view thereof taken on the line 2—2 of Fig. 1;

Fig. 3 is a perspective view of the stud-plate unit, detached;

Fig. 4 is a similar view of a pierced blank from which the stud-plate unit of the preceding figures may be formed;

Fig. 5 is a sectional view similar to Fig. 2, and showing another form of stud-plate unit embodying the present invention; and

Fig. 6 is a perspective view of the stud-plate unit of Fig. 5.

The showing of Figs. 1 to 4 inclusive

In the device of Figs. 1 to 4 inclusive, a stud-plate 10 is provided which includes a transverse upper-bar 11, a transverse intermediate-bar 12 and a transverse lower-bar 13. All three of these bars 11, 12 and 13, just referred to, are integrally united by side-bar portions 14—14.

Vertically between the upper-bar 11 and the intermediate-bar 12 is an upper web-receiving slot or passage 15 adapted to have a reach of webbing threaded therethrough, in a manner as will more fully hereinafter appear. Vertically be-

tween the intermediate-bar 12 and the lower-bar 13, the stud-plate is also formed with a lower web-receiving slot or passage 16 also adapted to have a reach of webbing threaded therethrough.

5 Formed integral with and bent outwardly away from the front-face of the stud-plate 10 is the inner-arm 17 of an L-shaped stud-projection, generally designed by the reference character 18. The inner-end of the inner-arm 17 is integrally united with the upper-edge of the intermediate-bar 12. The said stud-projection 18 also includes an outer-arm 19 formed integral with and bent downwardly from the outer-end of the inner-arm 17 into parallelism with the front-face of the 10 stud-plate 10 toward and over the slot 16 and the lower-bar 13 of the said stud-plate. The said outer-arm 19 of the L-shaped stud-projection 18 is wider than the inner-arm 17 thereof, so as to provide two oppositely-extending projections 15 which may be aptly designated as retaining-ears 20—20, respectively located on the opposite sides of the said arm 19.

The stud-plate 10, with its integral L-shaped stud-projection 18, may be conveniently produced 25 from sheet-material such as sheet-brass, sheet-steel, sheet-synthetic-resin, etc., by piercing out a blank 21 such as is shown in Fig. 4. For a ready understanding of the relationships between the blank 21 and the fully-formed stud-plate 10 and the stud-projection 18, similar reference characters have been applied to Fig. 4 plus the reference character "a," in order to identify the parts of the blank 21 from which the corresponding features of the stud-plate 10 and its stud-projection 18 are formed.

35 The preferred mode of utilizing the stud-plate 10 is to thread a suitable piece of web generally designated by the reference character 22, through its respective upper and lower web-receiving slots 15 and 16, in a manner best shown in Fig. 2. In 40 the figure referred to, it will be noted that the back-reach 22^a of the web 22 extends downwardly beneath the upper-bar 11 of the stud-plate 10 and also beneath the intermediate- and lower-bars 12 and 13 thereof. The web is then reversed around the lower-edge of the lower-bar 13, so as to constitute a second reach 22^b which extends upwardly across the front-face of the lower-bar 13 and thence rearwardly through the lower slot 16 and beneath the intermediate-bar 12 and then forwardly through the slot 15 and over the front-face of the upper-bar 11. A short distance above the upper-edge of the stud-plate 10, the reach 45 22^b of the web 22 is reversely bent to form a third reach 22^c which is itself wrapped around the 50 55

upper-bar 23 of a retaining-loop 24. The web is then turned upwardly across the front-face of the bar 23 to form a fourth reach 22^d which is brought into contact with the front-face of the third reach 22^c of the web. For purposes of securing the various reaches 22^a, 22^b, 22^c and 22^d together at a point immediately above the upper-bar 23 of the retaining-loop 24, one or more lines of stitching 25 are sewn through the web, as is shown in Fig. 2. The reaches 22^a and 22^b of the web 22 are preferably held together immediately above the upper-bar 11 of the stud-plate 10 by stitchings.

When the lower portion of the retaining-loop 24 is hooked over the stud-projection 13, the respective side-bars thereof will be retained against outward displacement by the respective retaining-ears 20—20.

The stud-plate unit of Figs. 5 and 6

The stud-plate unit of Figs. 5 and 6 comprises a stud-plate 27 which may be conveniently formed of sheet-material and which comprises complementary side-bars 28—28 between which laterally extend integral bars. The said bars include a single-thickness upper-bar 29, a double-thickness intermediate-bar 30 and a double-thickness lower-bar 31. The double-thickness bars 30 and 31 are produced by reversely folding the lower-edge of a suitable blank backwardly upon itself.

From the upper-edge of the front lamination of the intermediate-bar 30 is bent a stud-projection 32 formed on each of the respective sides of its outer-portion with a pair of complementary retaining-ears 33—33 adapted to function in the same manner as the retaining-ears 20—20 before referred to, in retaining the lower portion of a loop such as 24, against outward movement.

General considerations

After the stud-plate units, above described, are formed from sheet-material, it is preferred that they be given a finishing operation such as will round off all sharp edges. This finishing operation may be conveniently accomplished by tumbling the parts in a manner well understood in the art.

It will be understood that retaining-loops, such as 24, are applied over the front of the various stud-plate units after a portion of the garment has been first placed over the front- or outer-face of the said stud-plate unit. Under these conditions, the loop 24 or its equivalent will deflect the material of the garment around the stud-projection in such manner that the slippage of the garment relative to the stud-plate unit is effectively prevented under all but extraordinary strain.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A stud-plate unit for hose-supporters and the like, comprising: a stud-plate having a transverse lower bar, a transverse upper bar and a transverse intermediate bar, the said stud-plate having a lower web-receiving slot located between the said transverse lower bar and the said transverse intermediate bar and having a relatively small dimension in a vertical direction, the said stud-plate also having an upper web-receiving slot located between the said transverse intermediate bar and the said transverse upper bar and having a relatively large dimension in a vertical direction; and a stud-projection formed integral with the upper edge of the said transverse intermediate bar of the said stud-plate and formed from material displaced from the said relatively large upper web-receiving slot, the said stud-projection extending outwardly and downwardly from one face of the said intermediate bar toward the said lower bar and into position for entry into the loop of a hose-supporter or the like.

2. A stud-plate unit for hose-supporters and the like, comprising: a stud-plate having a transverse lower bar, a transverse upper bar and a transverse intermediate bar, the said stud-plate having a lower web-receiving slot located between the said transverse lower bar and the said transverse intermediate bar and having a relatively small dimension in a vertical direction, the said stud-plate also having an upper web-receiving slot located between the said transverse intermediate bar and the said transverse upper bar and having a relatively large dimension in a vertical direction; and an L-shaped stud-projection formed integral with the upper edge of the said transverse intermediate bar of the said stud-plate and formed from material displaced from the said relatively large upper web-receiving slot, the said stud-projection having one arm extending laterally outwardly away from one face of the stud-plate, the said stud-projection also having a second arm integral with the outer end of the first-mentioned arm and projecting therefrom toward the lower bar of the said stud-plate.

WALTER S. PAINTER.
